DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corpora-
tion of New Jersey

Application June 19, 1936, Serial No. 63,385

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in alternate areas, extending vertically of the fabric, of plain weave and weaves at an angle producing characteristic stripes throughout alternate areas at a slight angle to the vertical.

I claim:

The ornamental design for a textile fabric or similar article of manufacture, substantially as shown and described.

JOHN F. GAUL, JR.
